UNITED STATES PATENT OFFICE

2,498,125

CONTAINER FOR PIGMENTED LIQUIDS

Percy E. Knudsen, Pittsburgh, Pa., and Earl H. Heaton, Ferndale, Mich., assignors to Pittsburgh Plate Glass Company, Allegheny County, Pa., a corporation of Pennsylvania

Application February 15, 1947, Serial No. 728,876

6 Claims. (Cl. 259—8)

1

The present invention relates to containers and it has particular relation to portable containers for shipping and storing liquids which contain heavy pigments likely to settle out of the liquids during transportation and storage.

One object of the invention is to provide a portable container for pigmented liquids in which the contents of the container can conveniently be agitated in order to obtain uniform dispersion of pigmentary materials in the liquid medium.

A second object is to provide an agitator device which is well adapted to keep the contents of the container thoroughly stirred, but which can be inserted in or removed from the container through a comparatively small opening.

A third object of the invention is to provide a container of relatively sturdy construction which can conveniently be picked up and handled by mechanical means during such operations as weighing, transporting and shipping or preparatory to storage and without the use of pallets or similar devices for supporting the containers.

A fourth object of the invention is to provide a portable container for paints and other pigmentary materials that can conveniently be emptied by mechanical means.

A fifth object is to provide a portable container for paints and such like pigmented liquids that can be stacked and stored with maximum convenience and with maximum security and economy of space.

These and other objects of the invention will be apparent from consideration of the following specification and claims.

In the handling and storage of such pigmented liquids as paints and lacquers and notably of compositions employed in the coating of automobiles, it is often desirable to handle and store considerable volumes of the materials. Heretofore barrels or drums have been employed for the purpose. However, the compositions are so heavy, that for conventional methods of handling, the sizes of the containers must be limited for example to about 55 gallons. Even these containers when so charged are exceedingly heavy for conventional handling by manpower operations. The containers are but poorly adapted for manipulation by mechanical means since they conventionally are not provided with adequate means to facilitate insertion of lifting trucks or forks under the containers. Moreover, the sizes are not well adapted for economical mechanical handling. Also, the containers usually are bulged or have projecting rims or flanges that are uneconomical of space in storage and ship-

2

ping operations and which render the stacks unstable.

The present invention contemplates the provision of a container which is ideally suited for manipulation by mechanical equipment and which can be stored by piling or stacking with maximum of security and in minimum space. These effects are attained by formation of the containers with cylindrical sides and substantially flat bottom and top portions secured together in an essentially integral manner, for example, by welding to the cylindrical side wall whereby to provide containers free of projections that would consume unnecessary space and to provide top and bottom surfaces that are flat and excellently adapted for stacking operations with a maximum stability of the piles. The invention further contemplates the provision of skids upon the flat bottom structures designed to admit of convenient insertion of lifting apparatus under the containers and further being designed to act as fulcrums permitting the satisfactory tipping of the containers to pour out the contents. As another feature the invention contemplates the provision of an agitator structure that can be inserted and withdrawn from the container through relatively small manholes that can conveniently be covered and sealed by means of comparatively small plates and gaskets that are easy to remove or replace.

For a better understanding of the invention, reference may now be had to the accompanying drawing in which Figure 1 is a sectional elevation view of a container constructed in accordance with the provisions of the invention. Figure 2 is a plan view of the top of the container shown in Figure 1. Figure 3 is a detail view of a spider suitable for carrying the agitator arms shown in Figure 1.

In the drawing, like numerals refer to like parts throughout. The construction as indicated in Figure 1 comprises an outer shell 10 which preferably is formed of relatively strong metal such as steel and which usually will be of substantial thickness in order to assure adequate strength for admitting of mechanical handling and stacking of the containers without denting. A thickness of about $\frac{1}{8}$ " is usually satisfactory for containers of a capacity of about one ton which is a convenient size for handling by most mechanical hauling and hoisting equipment.

The top and bottom of each container comprises plate like portions 11 and 12, preferably smooth or nearly so and having cylindrical rim portions 13 and 14, usually of the same diameter

as the side wall portion and having edges to mate with the edges of the side wall. The rims may be joined to the edges of the side wall by welding or by brazing (indicated at 15) in such manner as to provide an essentially integral structure which is substantially free, at least on the inner surface, of cracks and seams that would tend to retain paints or other materials. The smoothness of the seams between the flanges of the top and bottom and the side walls may be enhanced 10 by grinding or by working with other tools if so desired.

The top portion is formed with a pouring spout 16 at or near the edge thereof and which may be secured about a suitable opening in the 15 top by means of welding or brazing as indicated at 17. This spout is closed by means of a plug 18 threaded into the spout and being provided with a securing chain 19 in order to prevent its loss.

In order to admit of access to the interior of the container and also to admit the insertion of an agitator indicated generally at 21 a man-hole 22 is formed in the top, and may be closed by a plate like member 23, which rests upon a 25 suitable sealing gasket 24 between the top 11 and the plate. The plate is clamped against the gasket by means of bolts 26 having nuts 27 threaded thereupon.

A depression 28 is formed in the plate 23 at 30 the center thereof and is coaxial with the axis of the container. This depression has an opening formed therein constituting a bearing for the shaft 29 of the agitator 21. The shaft is disposed in sleeve 29a and is locked from rotation in the sleeve by pins 29b. The upper extremity of this shaft is formed with a non-circular, e. g. rectangular portion 30, designed to fit in a socket or chuck of a driving device (not shown) and is covered by a screw threaded plug 31, which is threaded into the depression 28 and functions to prevent the escape of the contents of the container about the upper extremity of the shaft. At its lower extremity the shaft 29 is journaled in a thrust bearing 32, which is secured to the bottom plate 12 of the container and is enclosed by a housing or shield 32a.

The agitator shaft carries a casting 33, which may be termed a "spider" secured upon the lower end thereof in convenient manner, for example, by means of set screws 34 or by a key in slot 34a or other suitable device designed to prevent relative rotation between the shaft and the spider. The spider has bolt holes 35 formed therein and as shown in Figure 3, has machined vertical faces 36 and 37 upon which the inner extremities of radial agitator arms 38 and 39 slide. These arms are pivotally secured to the spider by means of bolts 41 and 42 extending through holes 35. The arms, preferably, are of a length to reach approximately to the outer wall of the container but sweep freely within the latter. Also, the lower edges of the arms are designed just freely to clear the bottom surface of the container whereby to prevent caking of pigment upon the surfaces. The arms may, as shown in Figure 1, have downwardly inclined surfaces 44, that terminate in a lower edge 46 in such manner as to assist in picking up any pigmentary material tending to collect on the bottom of the container.

In order to maintain maximum agitation of the contents of the container when the shaft 29 is rotated, the arms may also be provided with upwardly extended blades 47, that may be

disposed in a plane at an angle to the radius of the drum in such manner as to impel the material with which the arms contact inwardly or outwardly as may be desired. It will be apparent that the blades on one of the arms 39 are designed to pass upon one side of the shaft 29 when the arm 39 is swung upwardly to the broken line position shown at X in Fig. 1 while the members 47 upon the other arm are designed to pass upon the other side of the shaft so as to admit of folding the two arms into compact unit which will freely pass through the manhole 22.

For the purposes of admitting a fork or a lifting platform under the container the bottom thereof is provided with supporting elements which may be termed "skids" indicated at 48 which usually are straight and of channel section, one flange of each channel being secured by welding or other appropriate methods to the bottom of the container. These members 48 are disposed in parallelism and are also so disposed that when one container is stacked upon the flat top surface of another, the skids of the top container will not interfere with the discharge spout 16 or the plug 31 or any other projecting surfaces associated with the top. The skids are spaced, as shown in Fig. 2, a distance from the axis of the container less than that from the axis to the spout. That is, each skid is on a chord of the circumference of the container. The skids 48, it will be apparent, constitute convenient reinforcements for the bottoms of the container. They also provide relatively broad surfaces providing a maximum of bearing surface upon the flat tops of the supporting containers when the containers are stacked. They further facilitate stacking, since they do not require to be brought into exact registry with the top on which they are seated in order to attain stability.

When it is desired to pour the contents of the container into another container, such as a reservoir of a paint spraying apparatus or into other smaller containers, it may be desirable to tilt the container forward. In the initial stages of tilting, the forward one of the skids may act as a fulcrum. To facilitate this pouring operation, a lug or lugs 52 may be secured, for example, by welding to the bottom of the container and may also be welded to the contiguous skid. This member 52 is formed with an opening 53, in which a hook of a chain hoist or other suitable hoisting equipment can be secured in order to admit of mechanical elevation of the side of the container to tilt the pouring spout forward.

If the contents of the container are to be discharged through the pouring spout it may be desirable to admit air to the container in order to prevent the atmospheric pressure from interfering with the pouring operation. To this end, as air vent 54 may be secured to the side of the container near the bottom thereof and contiguous to the lifting element 52. This vent is provided with a screw plug 56 tethered from loss by a chain 57. It will be apparent that the position of the vent 54 may be changed if desired but the position shown is convenient, since it constitutes a high point when the container is tilted well forward.

In the operation of the apparatus herein shown and described, the container may be disposed upon suitable scales of adequate capacity or upon any other support and paint or other 75 pigmented material filled into the container

through the pouring spout 16. When a sufficient amount of material has thus been filled into the container the plug 18 may be secured in place. The entire assembly can easily be lifted from the scale platform by a suitable lifting device such as a fork or a platform upon a lifting truck and carried to storage or to a loading platform for loading onto freight cars.

If it is desired to stack the containers, they may be lifted by mechanical means such as a fork truck previously referred to and stacked one upon the other so that the skids of the containers above rest upon the relatively smooth, flat surfaces of the containers below.

When it is desired to empty the container, the agitator mechanism 21 may be operated by any convenient source of power such as a separate vertical shaft (not shown) having a chuck acting upon the upper extremity of shaft 29, in order to stir up the contents of the container. When it is desired to pour out all or a portion of the contents, plug 18 is removed and a chain or other convenient hoist may be secured in the opening 53 so that the container can be tilted forward upon skid 48 as a fulcrum to permit the contents to run out into the desired receiver.

If the container is to be cleaned, or the agitator is for any reason to be removed, the bolts of the manhole cover 23 can be taken out, the agitator swung up and the whole assembly lifted out. The necessity of removing the entire head 11 is thus avoided.

The forms of the apparatus shown herein may be considered as typical or representative of the principles of the invention. It will be apparent to those skilled in the art that the forms of the invention herein illustrated are merely by way of example and that numerous modifications may be made therein without departure from the spirit of the invention or the scope of the appended claims.

We claim:

1. A container for storage and shipment of liquids, said container comprising a cylindrical side wall, substantially flat top and bottom walls integral with the side wall and being free of projecting rims, a pouring spout projecting upwardly at the edge of the top, a pair of spaced parallel skids on the bottom disposed perpendicular to a plane bisecting the container through the pouring spout, said skids being secured to the bottom of the container each skid being spaced from the axis of the container a distance less than that from the axis to the spout, said skids being in position to admit insertion of lifting mechanism under the container and being designed to rest upon the top of a second container corresponding to the first with the bottom of the first out of contact with the pouring spout of the second.

2. A container for storage and shipment of liquids, said container comprising a cylindrical side wall, substantially flat top and bottom walls integral with the side wall and being free of projecting rims, a pouring spout projecting upwardly at the edge of the top, a pair of spaced parallel skids on the bottom disposed perpendicular to a plane bisecting the container through the pouring spout, said skids being secured to the bottom of the container each skid being spaced from the axis of the container a distance less than that from the axis to the spout, said skids being in position to admit of insertion of lifting mechanism under the container and being designed to rest upon the top of a second container corresponding to the first with the bot-

tom of the first out of contact with the pouring spout of the second and means for attaching a lifting device to the bottom of the container at a point in a plane extending through the pouring spout and bisecting the container whereby the container can be tilted forwardly about the forward of said skids as a fulcrum to empty the contents through the pouring spout.

3. A container for storage and shipment of liquids, said container comprising a cylindrical side wall, substantially flat top and bottom walls integral with the side wall and being free of projecting rims, a pouring spout projecting upwardly at the edge of the top wall, a pair of spaced parallel skids on the bottom disposed perpendicular to a plane bisecting the container through the pouring spout, said skids being secured to the bottom of the container each skid being spaced from the axis of the container a distance less than that from the axis to the spout, said skids being in position to admit insertion of a lifting mechanism under the container and being designed to rest upon the top of a second container corresponding to the first with the bottom of the first out of contact with the pouring spout of the second and means for attaching a tilting device to the bottom of the container at a point in a plane extending through the pouring spout and bisecting the container, whereby the container can be tilted about the forward of said skids as a fulcrum to empty the contents through the pouring spout and an opening near the last mentioned means and a plug disposed in the opening whereby when the container is tilted to drain the contents, air can be admitted to the space above the contents.

4. A container for storage and shipment of paints, said container comprising a cylindrical side wall and substantially flat top and bottom plates secured to the side wall, a manhole cut in the top plate, an agitator shaft disposed in a bearing formed in the plate, said agitator shaft at its lower extremity being journaled in a thrust bearing upon the bottom of the container, said agitator shaft contiguous to its lower end being provided with a spider rigidly secured thereupon, a pair of oppositely disposed agitator arms pivoted for individual vertical swinging movement upon the spider toward the shaft, the arms at their outer extremities being provided with vertically disposed blades, the blades upon one arm being disposed to pass upon one side of the shaft while those upon the other arm are disposed to pass on the other side of the shaft when the arms are swung upwardly whereby to permit the agitator to be withdrawn through the manhole when the arms are swung upwardly, said arms extending approximately to the cylindrical wall when they are lowered.

5. A container for storage and shipment of paints, said container comprising a cylindrical side wall, flat top and bottom plates having cylindrical flanges welded to the contiguous edges of the side wall, straight skids disposed in parallel relation upon the bottom, a spout upon the top disposed in a plane bisecting the skids and being disposed at the edge of the plate, the skids being disposed to rest upon the top of a corresponding container between the spout and the axis of the container while the other skid is equally spaced from said axis and a lifting lug secured to the bottom plate whereby the container can be tilted forwardly to pour the contents through said spout.

6. A container for storage and shipment of paints, said container comprising a cylindrical

side wall, flat top and bottom plates secured to the side wall, a pair of parallel skids secured to the bottom plate, a spout upon the upper plate contiguous to the edge thereof and being disposed in a plane bisecting the skids, the skids being disposed to rest upon the top of a corresponding container between the axis of the container and the spout while the other skid is equally spaced from said axis, a lifting lug secured upon the bottom plate whereby the container can be tilted forwardly to pour the contents through the spout, said container further being provided with an air vent also disposed in the plane bisecting the skids contiguous to the bottom edge.
